(57) **CLAIM**

The ornamental design for a low-voltage light, as shown and described.

DESCRIPTION

FIG. 1 shows an isometric front view of a low voltage light having the design of the present invention.

FIG. 2 depicts an isometric rear view of a low voltage light having the design of the present invention.

FIG. 3 is a top side view of a low voltage light having the design of the present invention.

FIG. 4 presents a right side view of a low voltage light having the design of the present invention.

FIG. 5 shows a bottom view of a low voltage light having the design of the present invention.

FIG. 6 depicts a left side view of a low voltage light having the design of the present invention.

FIG. 7 is a rear view of a low voltage light having the design of the present invention; and,

FIG. 8 is a front view of a low voltage light having the design of the present invention.

The broken lines shown on the drawings depict portions of the low-voltage light that form no part of the claimed design.
